(57) **CLAIM**

The ornamental design for a self-watering flowerpot, as shown and described.

DESCRIPTION

FIG. 1 is a top, front, left side perspective view of a self-watering flowerpot, showing my new design;

FIG. 2 is a bottom, rear side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is another perspective view showing the self-watering flowerpot and its reservoir separately.

The broken lines in FIGS. 2, 8, and 9 depict portions of the self-watering flowerpot that form no part of the claimed design.
